UNITED STATES PATENT OFFICE

107,618

DESIGN FOR A DRESS

Philip Schlessel, New York, N. Y.

Application November 11, 1937, Serial No. 72,804

Term of patent 3½ years

To all whom it may concern:

Be it known that I, Philip Schlessel, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the specific quilted ornamentation on the sleeves and waist portion as shown.

I claim:

The ornamental design for a dress, substantially as shown and described.

PHILIP SCHLESSEL.
